(Cl. D44—24)

To all whom it may concern:

Be it known that I, Arthur P. Cary, a citizen of the United States of America, residing at Dallas, in the county of Dallas and State of Texas, have invented a new, original, and ornamental Design for a Holder for Paper Napkins or Similar Articles, of which the following is a specification, reference being had to the accompanying drawing, forming a part thereof.

Fig. 1 is an end elevational view of a holder for paper napkins or similar articles, showing my new design.

Fig. 2 is a top plan view of the holder,

Fig. 3 is a side elevational view of the holder, and

Fig. 4 is an underside plan view of the holder.

I claim:

The ornamental design for a holder for paper napkins or similar articles, as shown.

ARTHUR P. CARY.
